UNITED STATES PATENT OFFICE.

ORLANDO W. BEDELL, OF NEW YORK, N. Y., ASSIGNOR TO ELY-NORRIS SAFE COMPANY, OF PERTH AMBOY, NEW JERSEY, A CORPORATION OF NEW JERSEY.

SAFE.

No. 909,523.

Specification of Letters Patent.

Patented Jan. 12, 1909.

Application filed February 19, 1908. Serial No. 416,653.

To all whom it may concern:

Be it known that I, ORLANDO W. BEDELL, a citizen of the United States, residing in the city of New York, county of Richmond, 5 and State of New York, have invented certain new and useful Improvements in Safes, of which the following is a specification.

This invention relates to safes, vaults and the like, and the object of the invention is to effect certain improvements in the construction of the doors of safes and vaults with respect particularly to the devices whereby the combination lock is operated from the exterior of the door.

In safes and vaults it is common to provide a combination lock within or on the inner face of the door and a shaft or spindle connected to this lock passes through an opening in the door and is provided with a handle on its outer end for turning it to operate the lock. The provision of these moving parts which may be manipulated from the exterior of the door and an opening extending through the door to receive the spindle has always introduced an element of weakness, as it involves an additional crack into which an explosive in liquid or gaseous form may be injected, since the spindle and the parts connected thereto may 25 usually be broken more easily than the door itself and access to the interior of the safe in that way gained. For this reason the construction and arrangement of the parts extending through the door and connecting 30 with the combination lock for operating the latter are of great importance. In accordance with my invention, connecting devices from the exterior of the door to the combination lock are provided which are of an 35 improved construction, this being characterized by marked simplicity, great strength and capacity to effectually resist rupture and derangement of the parts from the exterior of the door; furthermore, with my improved 40 construction, the parts may be readily assembled and for this reason, as well as for the reasons that but a small number of parts are employed and these are of simple form, the cost of production is quite low.

In some instances, the doors of safes and vaults have been provided with chambers therein, preferably nearer the front than the rear face, for the expansion of gases present in an explosion, so that in such a safe, an 50 explosion would result in blowing off the

portion of the door forward of the chamber and leaving the portion in rear thereof intact. In the preferred embodiment of my invention, this construction of door is adopted and the combination lock is placed within this chamber; in this case, the spindle passing through the forward portion of the door has its inner end bearing against the inner wall of the chamber to assist in positively positioning the spindle.

The preferred embodiment of my invention is illustrated in the accompanying drawings, in which—

Figure 1 is a sectional elevation of a portion of the door and wall of a safe and Fig. 2 70 is a detail view hereinafter referred to, partly in elevation and partly in section.

Referring to these drawings, 1 indicates the wall of a safe formed to have the door 2 coact therewith to close the safe with a tight 75 joint. The door 2 is of any suitable construction and may be arranged to swing to the closed position on pivots and then turn on its axis to lock it. In the door 2 are one or more chambers 3, the several chambers preferably communicating and being located somewhat nearer the front than the rear face of the door. These chambers permit of the expansion and combustion therein of the gases present in an explosion and such explosion and expansion of gases, if sufficiently 80 severe, will result in blowing off the portion of the door in front of the chambers and leaving the portion in rear thereof intact. The door is preferably held in place by two 85 locks, a time-lock 4 and a combination lock 5, the former being secured to the rear face of the door and the latter being mounted within the chamber 3. The time-lock 4 is adapted to control the movement of bolts 6, 90 said bolts being adapted to be moved radially of the door in suitable guides 7 on the door, such movement carrying the ends of the bolts into and out of openings in the door-jamb. The combination lock 5 is of the usual or any 95 suitable construction and operates to move bolts 8 radially of the door in suitable guides to carry their ends into and out of openings in the door-jamb. The lock 5 here shown has a group of notched tumbler disks with 100 which a lever 18 coöperates to move the bolts 8. The first one of the notched tumbler disks is provided with a gear 9 by which it is directly rotated and inter-connecting mechanism is provided between the several tum- 110

blers whereby when the operating handle has been turned in one direction to the proper extent and the direction of rotation reversed, the next tumbler will be picked up and rotated with the one or more which had been rotating.

The present invention concerns more particularly the mechanism for rotating gear 9. An opening is provided through the outer portion of the door from the chamber 3 to the front face of the door and this opening receives and forms a bearing for a spindle 10 by which the combination lock is operated. The outer end of the spindle is reduced and squared to receive an operating handle 11, the edge of which is provided with scale markings and cooperates with marks on an annulus secured to the face of the door. At its inner end, spindle 10 is provided with an integral threaded portion 12 and, beyond this at the extreme end of the spindle, is an integral bearing-piece 13 of polygonal section, here shown as square. Threaded on the portion 12 is a sleeve 14 the bore of which is suitably threaded and on the exterior of this sleeve is formed an integral gear 15. A cap 16 lies against the end of sleeve 14 and has a square opening therein through which the bearing-piece 13 extends. At its edge, cap 16 has an integral flange overlying the sleeve 14 as shown, and screws 17 pass through openings in this flange and into tapped openings in sleeve 14 to hold the sleeve and cap together, screws 17 lying at a right angle to the axis of the spindle. These parts are assembled by placing the cap 16 on sleeve 14 but not fastening it with screws 17, then passing the two parts into the chamber 3 and holding them in position, as with a long pair of pincers, and then inserting the spindle 10 in its opening until its end enters the opening in sleeve 14. Then by turning the spindle, the threads on the portion 12 and on the sleeve engage and draw the spindle inward until its reduced end passes through the opening in cap 16. During the further turning movement of spindle 10, cap 16 turns with it and the spindle is drawn inwardly until its inner end bears against the inner wall of the chamber 3. With the holes in cap 16 and sleeve 14 in alinement, the screws 17 are inserted in position and tightened to hold the two parts together.

It will be seen that by this construction, the spindle 10, while free to be rotated in the opening in the door, is positively held against axial movement, since such movement in one direction is precluded by the coaction of bearing-piece 13, which may be of hardened steel, with the inner wall of the chamber 3, and in the other direction by the sleeve 14 which is of greater diameter than the opening in the door for the spindle and therefore bears against the outer wall of chamber 3. Spindle 10 cannot be turned relatively to

sleeve 14 because of the coaction of the squared piece 13 integral with the spindle with the opening in cap 16 and the screws 17 securing the cap to the sleeve; any turning movement of spindle 10 must therefore result in turning sleeve 14, gear 15, gear 9 and one or more of the tumbler disks. The construction is simple and the number of parts quite small, so that the manufacturing cost is low; also, the strength and arrangement of the parts of the structure is such that the danger of breaking or displacing the parts and thereby operating or breaking the lock to release the door is reduced to a minimum.

Having now described my invention, what I claim as new therein and desire to secure by Letters Patent is as follows:

1. In a safe, a door, a spindle passing therethrough having a portion provided with a flattened wall, a sleeve on said spindle, a cap having an opening therethrough to receive said spindle and formed to coact with said flattened wall to preclude turning of the cap on the spindle, means for securing the cap and spindle together; and lock-operating means on said sleeve, substantially as set forth.

2. In a safe, a door having a chamber therein intermediate the front and rear faces thereof, a spindle passing through an opening in the door from the front face thereof to said chamber and provided with a flattened wall, a sleeve on said spindle, a member provided with an opening to receive said spindle and formed to coact with said flattened wall to preclude turning of the member on the spindle, means for securing the member and spindle together, and lock-operating means on said sleeve, substantially as set forth.

3. In a safe, a door, a spindle passing through an opening therein and having an integral threaded portion and an integral portion of polygonal cross-section, a sleeve threaded on said threaded portion, a cap having an opening therein corresponding in shape to said portion of polygonal cross-section and through which said portion extends, said cap lying adjacent to one end of said sleeve, screws securing the cap and sleeve together and lying at substantially a right angle to the axis of the spindle, and lock-operating means on said sleeve, substantially as set forth.

4. In a safe, a door having a chamber therein intermediate the front and rear faces thereof, a spindle passing through an opening in the door from the front face thereof to said chamber, a sleeve on the inner end of said spindle within said chamber, means for connecting the sleeve and spindle and positively preventing relative movement thereof, and lock-operating means on said sleeve, substantially as set forth.

5. In a safe, a door having a chamber

therein intermediate the front and rear faces thereof, a spindle passing through an opening in the door from the front face thereof to said chamber, the end of said spindle bearing against the inner wall of said chamber, a sleeve of greater diameter than said opening threaded on said spindle within said chamber, means for connecting the sleeve and spindle and positively preventing relative movement thereof, and lock-operating means on said sleeve, substantially as set forth.

6. In a safe, a door having a chamber therein intermediate the front and rear faces thereof, a spindle passing through an opening in the door from the front face thereof to said chamber and having a portion provided with a flattened wall, the end of said spindle bearing against the inner wall of said chamber, a sleeve of greater diameter than said opening on said spindle within said chamber, a member on the spindle within the chamber coacting with said flattened wall to prevent turning of the member relatively to the spindle, means for securing said member to said sleeve, and lock-operating means on said sleeve, substantially as set forth.

7. In a safe, a door having a chamber therein intermediate the front and rear faces thereof, a spindle passing through an opening in the door from the front face thereof to said chamber and having an integral

threaded portion thereon within said chamber and a portion provided with a flattened wall and bearing against the inner wall of said chamber, a sleeve threaded on said threaded portion, a cap on the spindle adjacent to said sleeve and coacting with said flattened wall, screws securing the cap to the sleeve and lying at substantially a right angle to the axis of the spindle, and lock-operating means on said sleeve, substantially as set forth.

8. A safe having a door adapted to enter an opening in the wall thereof, and composed of two or more integral door sections having a chamber between them extending outwardly adjacent to the periphery of the door, a combination lock mounted upon said door within said chamber, means for operating the combination lock from the exterior of the door, and a time-lock independent of said combination lock mounted on the rear face of the rear section of said integral door, each of said locks having its individual bolt-work, and the ends of the bolts of both of said locks being adapted to coact with the door-jamb to secure the door in the closed position, substantially as set forth.

This specification signed and witnessed this 17th day of February, 1908.
